 Lance, Inc., Charlotte, N. C., a corporation of
 North Carolina

Application October 17, 1951, Serial No. 251,725

9 Claims. (Cl. 107—29)

1

This invention relates to apparatus for applying a paste or viscous filler or coating, such as peanut butter and the like, to crackers, wafers and similar articles and more especially to an improved dispensing apparatus therefor.

This application is a continuation-in-part of my co-pending application, Serial No. 236,617, filed July 13, 1951, and entitled Improved Sandwich Making Machine.

Heretofore, many attempts have been made to perfect a suitable apparatus for depositing coatings of viscous material such as paste, peanut butter and the like, upon wafers, crackers and the like, wherein a coating of substantially uniform thickness, length and width was provided upon each of a plurality of wafers, crackers or the like which were passed beneath the dispensing apparatus in rapid succession. However, many difficulties have been encountered and, particularly, in the instance of peanut butter being used as the filler or coating material, the means heretofore provided on the dispensing means for severing or otherwise separating each portion of the coating material or filler from the bulk of the filler or coating material disposed in the dispensing apparatus has been of such construction that the filling material would tend to cling to the severing means and, since peanut butter is an extremely adhesive material as well as an extremely cohesive material, the peanut butter would tend to cling to the walls of the orifice through which it was dispensed from the dispensing apparatus.

This would not only require stopping the machine at frequent intervals for cleaning the dispensing mechanism but would, in some instances, also cause a substantial portion of the filler dispensed through the discharge orifice of the dispensing mechanism to tear apart from the dispensed portion each time the orifice was opened, with the result that the wafer or cracker would only be partially coated with the coating material or filler.

It is, therefore, the primary object of this invention to provide an improved dispensing apparatus for viscous materials, such as peanut butter and the like, wherein a unique means is provided for parting the viscous material upon predetermined portions thereof being dispensed through the discharge opening or orifice of the dispensing apparatus and wherein the dispensing apparatus has means for directing the viscous material through the discharge openings or orifices thereof under constant pressure.

This unique means for parting the extruded portions of the filler or coating material from the bulk of material disposed within the dis-

10 pensing apparatus differs primarily from parting means heretofore employed in that the size of the opening or orifice through which the material is dispensed is rapidly decreased in size and in its process, the viscous material is compressed at said orifice or opening until the opening is completely closed. This causes the extruded portions of the viscous material to be tapered slightly at the trailing edges thereof and to be parted from the bulk of the viscous material by squeezing or compressing the viscous material at the juncture of the extruded portion thereof and the bulk thereof or at the opening or orifice.

15 It is another object of this invention to provide an improved dispensing apparatus adapted to be associated with a machine having a conveyor thereon for successively moving wafers or crackers beneath the dispensing apparatus, the dispensing apparatus being in the form of a gear pump having a cavity or chamber therein adapted to contain a supply of viscous material, such as peanut butter and the like, and being also provided with a discharge opening or orifice which is normally closed by a vertically movable gate member. Suitable passageways are provided in the gear pump and suitable gears therein direct the viscous material under pressure to the discharge opening or orifice. The pump is also provided with other passageways for directing or circulating the viscous material back into the chamber from whence it came when the gate is in a closed position.

20 A relatively thin member or plate defines the bottom of the passageway which directs the viscous material from the chamber to the discharge opening or orifice and means are provided for directing the cracker or wafer closely beneath said relatively thin member or plate. One edge of said plate also defines the bottom of said discharge opening or orifice and when the gate is in a closed position, the flat lower surface thereof engages the upper surface of said plate and the exterior surface or the gate is flush with the corresponding vertical edge of the relatively thin member or plate. Means are provided for raising or opening the gate at predetermined intervals, whereupon the viscous material is forced out of the dispensing apparatus through the opening defined by the lower edge of the gate and the upper surface of the relatively thin member or plate and, upon a predetermined length of the viscous material being extruded through said opening, the gate is permitted to move downwardly and, in so doing, this gate squeezes or compresses the viscous material

against the upper surface of the bottom or relatively thin member or plate to ultimately part the length of extruded viscous material from the viscous material in the passageway leading to the discharge opening or orifice.

This not only causes the viscous material to be cleanly parted but since the wafer or cracker is disposed in very close proximity to the lower edge of said gate, the viscous material is not separated or parted with a ragged or rough edge and, consequently, does not adhere to the exterior edges of the discharge opening or orifice defined by the proximate surfaces of the gate and the relatively thin member or plate.

Some of the objects of the invention having been stated, other objects will appear as the description proceeds when taken in connection with the accompanying drawings, in which—

Figure 1 is a fragmentary elevation of a portion of a sandwich making machine of the type shown in said co-pending application and showing the improved filler or coating dispensing apparatus mounted thereon;

Figure 2 is an enlarged top plan view of the central portion of Figure 1 showing the improved filler or coating dispensing apparatus but omitting the hopper and the conveyor therefrom for purposes of clarity;

Figure 3 is an enlarged longitudinal vertical sectional view through the improved dispensing apparatus taken substantially along the line 3—3 in Figure 2, but showing the gears and gate latch in elevation, and showing portions of the wafer or cracker propelling means in association therewith schematically, and also showing the manner in which the hopper is secured to the upper surface of the filler or coating dispensing apparatus;

Figure 4 is an isometric view of the filler or coating dispensing apparatus disassociated from the sandwich making machine and with many of the parts omitted for purposes of clarity;

Figure 5 is a fragmentary isometric view showing the manner in which the gates are mounted but omitting the main body portion or housing of the gear pump;

Figure 6 is an enlarged detail of the latching means shown in the upper right-hand portions of Figures 1 and 3 but showing the same in a different position;

Figure 7 is an enlarged sectional plan view through the dispensing apparatus taken substantially along the line 7—7 in Figure 1 but omitting the latch means and the means for driving the gears of the gear pump;

Figures 8, 9 and 10 are detailed views of the lower right-hand portion of Figure 3 showing the gate in successively lowered positions and illustrating the manner in which the extruded viscous material is parted as it is deposited upon a wafer, cracker or the like.

Although the dispensing apparatus is shown in the form of a gear pump, it is to be understood that means other than gears may be provided for directing the viscous material, such as peanut butter and the like, to the discharge opening or orifice of the dispensing apparatus. Referring to Figures 1, 2, 3 and 8 to 10, inclusive, there is shown a portion of a wafer or cracker coating machine or sandwich machine, the frame of which is broadly designated at 10. This sandwich machine or wafer coating machine may be of any desired construction and is shown as being substantially of the type shown in my said co-pending application, Serial No. 236,617. A similar machine is also

shown in my co-pending application, Serial No. 777,083, filed September 30, 1947, and entitled Sandwich Making Machine, now Patent No. 2,603,341, issued July 15, 1952. Since the machine illustrated in association with the present dispensing apparatus is clearly disclosed in said co-pending application, Serial No. 236,617, only so much of the machine is shown in the annexed drawings as is deemed necessary to a clear understanding of the present invention.

In this instance, the frame 10 comprises transversely spaced upper horizontally disposed side frame members 11 and 12 which are spanned by longitudinally spaced transverse track supporting bars 13, 14 and 15. The bars 13, 14 and 15 are spaced above the upper surfaces of the longitudinally extending side frame members 11 and 12 by respective pairs of spacing members, bars or supports 16, 17 and 18. The supports 16 are secured to the upper surfaces of the frame members 11 and 12, by any suitable means such as screws 21, and the supports 17 and 18 are penetrated by respective screws 22 and 23 which also penetrate the respective transverse bars 14 and 15 for securing these bars 14 and 15 and the supports 17 and 18 to the upper surfaces of the longitudinally extending frame members 11 and 12.

The transverse bar 13 is secured between the upper portions of the supports 16, by any suitable means such as screws 24, only one of which is shown in Figure 1. The transverse bar 13 supports a suitable wafer or cracker dispensing mechanism or magazine broadly designated at 25 which has suitable means including a connecting rod 26 for discharging cakes, crackers or other wafers therefrom one at a time onto a suitable conveyor broadly designated at 27.

This wafer dispensing apparatus 25 may be identical to the wafer dispensing mechanism shown in said co-pending application, Serial No. 236,617, and a detailed description thereof is deemed unnecessary. The convey mechanism or magazine 27 is preferably an endless type of conveyor comprising a pair of spaced endless carrier chains or endless belts 30 and 31 driven by conventional means, not shown, to move from left to right in Figure 1 in timed relation to the rate at which the wafers, crackers or the like are discharged from the wafer dispensing mechanism 25.

The chains 30 and 31 are bridged by a plurality of equally spaced transversely extending conveyor bars 140 suitably secured thereto which are caused to move along in a straight path in parallel relation to the longitudinally extending frame members 11 and 12 by suitable means not shown in the present drawing but being clearly shown in said co-pending application, Serial No. 236,617. The sandwich making or wafer coating machine shown in the drawings is designed for conveying two rows of crackers, wafers or the like along the trackways thereof to be presently described. It is to be understood, however, that the present filler dispensing apparatus may be associated with a machine having a lesser or greater number of trackways for conveying a lesser or greater number of rows of crackers, wafers and the like through the machine, as desired.

Since the portion of the conveyor 21 shown in Figures 1 and 7 may be construed as the upper reach of an endless conveyor, there is fixedly mounted in each of the bars 32 and extending radially therefrom two pairs of relatively closely spaced main conveyor pins or prongs 33, 34 and 33', 34'. It is to be understood that each of the

sets of main conveyor pins are arranged in rights and lefts, which is also the manner in which the trackways corresponding thereto to be later described are arranged.

Now, as the pins 33 and 34 move with the upper reaches of the conveyor carrier chains 30 and 31, they move along a trackway broadly designated at 35 while the pins 33' and 34' move along a trackway broadly designated at 35'. These trackways 35 and 35' may be identical to the trackways 152 and 152' shown in said copending application, Serial No. 236,617, and, therefore, only a general description thereof will now be given. Since the trackways 35 and 35' are identical, only the trackway 35 will be described and those parts of the trackway 35' which are identical to the parts associated with the trackway 35 will bear the same reference characters with the prime notation added.

The trackway 35 comprises a middle track 36, and outside tracks 37 and 38 which extend longitudinally of the machine. The outside tracks 37 and 38 are spaced from the middle track 153. It will be observed in Figure 7 that the outside tracks 37 and 38 are spaced so the pins 33 and 34 of the main conveyor 27 move between the outside tracks 37 and 38 and the middle track 36 and in closely spaced relation to the proximate surfaces of the tracks 37 and 38. These tracks 36, 37 and 38 are suitably supported by and depend from the transverse bars 14 and 15 and by other means clearly shown in said co-pending application, Serial No. 236,617.

The transverse bars 14 and 15 also serve to support transversely spaced longitudinally extending trackway guides 41 and 42 spaced from the outer vertical surfaces of the outside tracks 37 and 38. The upper edges of the trackway guides 41 and 42 are generally disposed at higher elevations than the upper edges of the relatively thin tracks 36, 37 and 38. The upper edges of the tracks 36, 37 and 38 are of identical configuration throughout their lengths with respect to each other and the trackway guides 41 and 42 are of identical configuration throughout their lengths with respect to each other. The upper ends of the pins 33 and 34, in the upper reach of the conveyor 31, project above the horizontal plane of the tracks 36, 37 and 38 and generally are disposed at a lower elevation than the upper edges of the trackway guides 41 and 42 to thereby propel crackers, wafers or the like, indicated at W, from left to right along the upper surfaces or edges of the tracks 36, 37 and 38, the trackway guides 41 and 42 being spaced according to the width of the wafer W.

It is to be noted in Figures 3, 8, 9 and 10 that the upper edges of the tracks 36, 37 and 38 are disposed in closely spaced relation to the lower surface of the improved filler dispensing apparatus to be presently described. As heretofore stated, the connecting rod 26 operates in timed relation to movement of the conveyor 27 from left to right in Figure 1 to cause wafers W to be discharged therefrom one at a time and these wafers fall onto the tracks 36, 37 and 38 between the trackway guides 41 and 42 in advance of each of the sets of conveyor pins 33 and 34 moving beneath the magazine or wafer dispensing mechanism 25 to thus cause the wafers W to move past the discharge end of the filler dispensing apparatus in rapid succession.

Filler dispensing apparatus

Assuming that the main conveyor 27 moves in 75 to provide front and rear inner vertical surfaces

a forward direction as it moves from left to right in Figure 1, there is disposed forwardly of the magazine or wafer dispensing mechanism 25 a filler or viscous material dispensing apparatus 5 comprising a housing or body portion broadly designated at 50, which may also be termed a gear pump. For purposes of assembly, the housing 50 is made in sections or blocks each preferably being of cast construction and comprising 10 outside or end blocks 51 and 52 of substantially L-shaped configuration and between which are disposed intermediate blocks 53 and 54 and a center block 55. If a single trackway is used, it is evident that the center block 55 and one 15 of the intermediate blocks could be omitted and the two outside blocks 51 and 52 could abut against the opposite sides of the remaining intermediate block.

During maintenance of the filler dispensing apparatus, it may become necessary to disassemble these blocks 51 to 55, inclusive, for cleaning or other purposes and, since it is necessary that all of the blocks are held in precise alignment with each other, the blocks 51 to 55, inclusive, are 20 collectively penetrated by dowel shafts or rods 56 and 57 (Figures 1 and 3) and are removably secured together by a plurality of bolts 60 which also collectively penetrate the blocks 51 to 55, inclusive, there being four of these bolts 60 shown 25 in Figure 3. A relatively thin member or plate 61, which may be construed as the base of the filler dispensing apparatus, is suitably secured to the lower surfaces of the blocks 53 to 55, inclusive, collectively as by screws 62. It will be observed in Figure 3 that the plate or base 61 extends substantially beyond the front vertical surfaces of the blocks 51 to 55, inclusive, for purposes to 30 be later described.

Since the housing 50 is preferably of less overall 35 width than the distance between the side frame members 11 and 12 of the frame 10, it will be observed in Figures 2, 3, 4 and 7 that the outer portions of the bottom plate or base 61 are secured to the upper surfaces of transversely spaced 40 longitudinally extending support or adaptor plates 63 and 64, by any suitable means, such as screws 65 which are threadably embedded in the outside or end blocks 51 and 52 of the housing 50. These plates 63 and 64 project outwardly substantially beyond the outer surfaces of the end blocks 51 and 52 and are suitably secured, as by 45 bolts or screws 66 to the upper surfaces of suitable spacing members 67 which are slidably penetrated by the screws 66. The screws 66 are 50 threadably embedded in the side frame members 11 and 12 to thus secure the respective adaptor plates 63 and 64 to the respective frame members 11 and 12 of the frame 10.

The spacing members 67 are provided in order 55 to space the base or plate 61 above the frame 10 sufficiently so that the upper surfaces of the tracks 36, 37 and 38 are disposed in closely spaced relation to the lower surface of the plate 61 as is clearly shown in Figure 3. The displacement between the upper edges of the tracks 36, 37 and 38 and the bottom of the plate 61 is slightly greater than the thickness of the crackers or wafers W. It will be noted that this bottom plate 61 is also spaced to provide clearance 60 for movement of the conveyor pins 33, 34, 33' and 34' therebeneath as is clearly shown in Figure 3.

Now, referring to Figures 3 and 4, it will be observed that the intermediate and center blocks 53 to 55, inclusive, of the housing 50 are cut away

70, 72 and 74, respectively, which define the front and rear walls of a cavity broadly designated at 76. The side walls of the cavity 76 are defined by the inner or proximate surfaces of the outside or end blocks 51 and 52.

The center block 55 has a horizontal upper surface 77 which defines the bottom of the corresponding portion of the cavity 76. However, the portions of the cavity 76 defined by the intermediate blocks 53 and 54 are of greater depth than the surface 77 of the center block 56 and each of the intermediate blocks 53 and 54 has a pair of arcuate cavities 80 and 81 therein which conform to the curvature of suitable pairs of intermeshing gear wheels 82 and 83, respectively (Figures 2 and 3). These gear wheels 82 and 83 may be of any desired type, however, it is preferable that helical gears be employed. The gears 82 are each fixedly mounted, as by a key 84, on an enlarged medial portion 85 of a common drive shaft 86 which has reduced end portions 87 integral therewith.

It will be observed in Figure 7 that the enlarged medial portion 85 of the drive shaft 86 penetrates the center block 55 and opposite ends of this enlarged medial portion 85 terminate in sliding engagement with the proximate surfaces of the outside blocks 51 and 52. The reduced end portions 87 of the shaft 86 penetrate the outside or end blocks 51 and 52, in which they are rotatably mounted, and each of the end blocks 51 and 52 has a boss portion 90 projecting outwardly therefrom on which a gland member 91 is threadably mounted. This gland member 91 holds a sealing member 92 against the outer end of the corresponding boss portion 90. The reduced portions 87 of the shaft 86 penetrate the corresponding boss portions 90, the sealing members 92 and the gland members 91 and also rotates therein.

The drive shaft 86 may be driven in any desired manner and is shown in Figures 1 and 2 as being driven in substantially the manner shown in said co-pending application, Serial No. 236,617. In this instance, each of the reduced portions 87 of the drive shaft 86 has a sprocket wheel 94 fixed thereon which is engaged by a sprocket chain 95. The sprocket chain 95 extends downwardly and also engages a sprocket wheel 96 which is fixed on a driven shaft 97 which may be driven in the manner shown in said last-named co-pending application.

In order to insure that the sprocket chain 95 is held under proper tension at all times, the sprocket chain 95 is engaged by a take-up sprocket wheel 100 which is rotatably mounted on one end of an arm 101 fixedly secured, as by a screw 102, to a block 103. The block 103 is suitably secured to the lower surface of the corresponding side frame members 11 and 12, as by screws 104. Since the driven shaft 97 may be supported for rotation and driven in any desired manner, such as the manner shown in said co-pending application, Serial No. 236,617, a further description thereof is deemed unnecessary.

Referring again to Figure 7, it will be observed that the gear wheels 83 mesh with the corresponding gear wheels 82 and each of the gear wheels 83 is fixedly mounted on an enlarged medial portion 107 of a shaft 108. Each of the shafts 108 has a reduced end portion 109 at each end thereof. The proximate or inner end portions 109 of the shafts 108 are rotatably mounted in the center block 55 and the outer end portions 109 of the shafts 108 are rotatably mounted

in the corresponding outside or end blocks 51 and 52.

It might be stated that, for best results, it is preferable that the shafts 86 and 108 are spaced accurately with respect to each other to insure that the pitch diameters of the gear wheels 82 and 83 properly coincide and to insure that there is a minimum of clearance between the gear wheels 82 and 83 and the corresponding arcuate cavities 80 and 81 to thereby insure that the viscous material will not solidify or congeal between the gear wheels 82 and 83 and the respective cavities 80 and 81. This is particularly important when peanut butter is used as the coating or filling material because the compressed peanut butter would ultimately "freeze" the gears against further rotation, otherwise.

Each of the intermediate blocks 53 and 54 of the housing 50 has a vertically extending bore or passageway 110 in the center thereof which is flared outwardly at its top portion to properly direct the filling material downwardly as the proximate portions of the mating gears 82 and 83 move downwardly in Figure 3. Thus, the viscous filling material is forced downwardly through the bore or passageway 110 and into a passageway 111 which extends forwardly to the discharge end of the housing 50. It will be noted that the bottom of this bottom passageway 111 is defined by the bottom plate 61 and each of the intermediate blocks 53 and 54 is cut away to form the top wall of the passageway 111 while opposed sides of the passageway 111 are defined by the proximate surfaces of the center block 55 and the corresponding outside or end blocks 51 and 52.

The front end of each of the blocks 51 to 55, inclusive, of the housing 50 has a forwardly projecting portion 112 thereon and there is secured to the front vertical surface of these portions 112, collectively, a gate support block or plate 113. This gate support block 113 may be integral with the blocks 51 to 55, inclusive, however, for simplicity of manufacture, it is preferable that a separate block be employed and the manner in which this block 113 is secured to the blocks 51 to 55, inclusive, will be later described.

The gate support block 113 has a passageway 114 in the inner or rear face thereof which communicates with the lower or bottom passageway 111 in each of the blocks 53 and 54 and which also communicates with a passageway 115, in the corresponding block 53 or 54, which is shown as being substantially Z-shaped in Figure 3. This passageway 115 extends upwardly and defines a return opening 116 in the front wall of the cavity 76 immediately above each of the front gear wheels 82 or at least above the points at which the front gear wheels 82 enter the corresponding cavity 80 in the blocks 53 and 54.

The upper horizontal and vertical branches of the passageway 115 may be formed by drilling through each of the intermediate blocks 53 and 54 of the housing 50 and, therefore, suitable plugs 120 and 121 are secured in each of the blocks 53 and 54 as by a pressed or sweat fit, to thus seal the upper horizontal and the vertical branches of the passageway 115.

The gate support block 113 has a discharge opening 122 in the bottom edge thereof coinciding with the groove 111 in each of the intermediate blocks 53 and 54. These discharge openings 122 are normally closed by vertically disposed relatively thin gates 123 and 123'. The gate 123 is disposed immediately above the track-

way 35 and the gate 123' is disposed above the trackway 35'. Although, gates of slightly varying thickness may be employed, it has been found most favorable that the material from which each of the gates 123 and 123' is made should be a relatively hard steel, approximately $\frac{5}{32}$ " thick. When more than one gate is employed, as is the case in the present instance, all of the gates should be accurately ground to a uniform thickness in order to insure that the gates may slide easily in a vertical plane while, on the other hand, insuring that the pressure of the peanut butter or other viscous filling material against the lower portion of the gate, when the gate is in a closed position as shown in Figure 3, will not cause the peanut butter or other viscous filling material from seeping past the edges of the corresponding gates 123 and 123'.

There are many different ways in which the gates 123 and 123' may be supported for vertical movement against the gate support plate 113. However, it is preferable that suitable spacing or guide plates 125 be disposed adjacent opposite side edges of the gates 123 and 123' and that these gate guide plates 125 should not be over $\frac{1}{1000}$ " thicker than the gates 123 and 123'. The gates 123 and 123' are held against the front or outer surface of the gate support plate or block 113 by means of a gate confining plate 126 which is suitably secured to the front surfaces of the gate guide plates 125 by screws 127.

The screws 127 slidably penetrate the corresponding gate guide plates 125 and are threadably embedded in the forwardly projecting portions 112 of the corresponding outside and center blocks 51, 52 and 55. It will be noted that the upper edges of the plates 113, 125 and 126 terminate in substantially the same horizontal plane and in substantially the same horizontal plane as the upper surfaces of the forwardly projecting portions 112 of the blocks 51 to 55, inclusive.

Although the lower edges of the plates 113 and 125 are disposed in engagement with the upper surface of the corresponding portion of the base plate 61, the lower edge of the gate confining plate 126 is spaced above the lower edges of the plates 113 and 125 to thereby permit the filling material to pass between the upper surface of the base plate 61 and the lower edges of the corresponding gates 123 and 123' when the gates are in raised or opened position. Of course, the size of the discharge openings are determined by the displacement between the lower edges of the gates 123 and 123' and the upper surface of the plate 61. Since the gate guide plates 125 must be positioned accurately with respect to each other to insure that the gates 123 and 123' slide in snug engagement therewith, it may be desirable to mount the gate guide plates 125 on the gate support plate 113 by means of dowel pins or the like and to provide holes for the screws 127 of slightly larger diameter than the screws 127 in the gate 125 for securing the gate assembly shown in Figure 5 to the front surfaces of the projections 112 on the blocks 51 to 55, inclusive, of the housing.

The most important feature of the present invention is that the bottom edge of each of the gates 123 and 123' is not sharp but is perfectly flat and engages the perfectly flat upper surface of the base plate 61 of the housing 50 when in closed position and the front surface of each of the gates 123 and 123' is disposed either flush with the front edge of the plate 61 or the lower edges of each of the gates 123 and 123' may

project very slightly beyond the front edge of the plate 61. However, the amount that each of the gates 123 and 123' may project beyond the front edge of the plate 61 when these gates are in closed position must not be any greater than is absolutely necessary and should not be over one or two thousandths of an inch.

Each of the gates 123 and 123' has secured therein, as by a pressed fit, and projecting forwardly therefrom, a spring anchor 130, to which the upper end of a tension spring 131 is connected. This tension spring 131 extends downwardly and its lower end is connected to a spring anchor 130a suitably secured in the gate confining plate 126, as by a pressed fit. Thus, the springs 131 normally urge the corresponding gates 123 and 123' downwardly to closed position in engagement with the upper surface of the base plate 61.

Since the gates are opened and closed in rapid succession, it will be noted that the front or foremost portion of the base plate 61 is secured to the lower surface of the gate support block or plate 113 by screws 132 in order to insure that the front portion of this base plate 61 will not bend downwardly or vibrate with the constant pounding of the gates 123 and 123' during operation of the sandwich making or wafer coating machine. In order to raise the gates 123 and 123' in timed relation to movement of the main conveyor, and to permit the gates to be moved downwardly by the corresponding springs 131, the gates 123 and 123' have respective slots or openings 134 and 134' in the exposed upper portions thereof which are preferably rectangular in shape and which are engaged by respective latch members 135 and 135'. Since these latch members 135 and 135' are mounted in an identical manner, only the latch member 135 will be described in detail and those parts associated with the latch member 135' will bear the same reference characters with the prime notation added.

The latch member 135 is shown in operative position in Figures 1, 2 and 3 and is shown in inoperative position in Figure 6. The pivoted latch 135 is preferably in the form of an elongated rigid member having a cavity 136 in the lower portion thereof defining a hook 137 on the lower end of the pivoted latch 135. The depth of this notch 136 is preferably equal to the thickness of the gate 123 and the height of the notch 136 is preferably substantially greater than the distance between the upper wall of the slot or opening 134 and the upper surface of the gate 123.

The upper portion of the pivoted latch 135 is fixedly mounted on a pin 140 pivoted in the outer or free end of a latch holder block 141 provided with a groove 142 at the outer end thereof and in which the upper portion of the pivoted latch 135 has sliding pivotal movement.

The latch holder block 141 has a reduced threaded portion 143 integral therewith which slidably penetrates a transverse gate latch support bar 144 and is secured therein as by a nut 145. The pivot pin 140 is oscillatably mounted in opposite walls of the notch 142 and has fixedly mounted thereon a latch control arm or knob 146 which is provided with a groove 146a therein.

The knob 146 has a spring anchor 147 thereon. The spring anchor 147 is disposed forwardly of the pin 140 and has one end of a tension spring 150 connected thereto which extends rearwardly and is connected to a spring anchor 151 projecting from one side of the latch holder block

141. The spring anchors 147 and 151 are so positioned with respect to each other that they would be in alignment with the pin 140 when the knob or control lever 146 projected outwardly in the plane of a line extending from the spring anchor through the pivot pin 140 and, consequently, the spring 150 will cause the control knob 146 to be urged either side of dead center relative to the pivot pin 140.

It is thus seen that when the control knob 146 is moved below dead center as shown in Figure 6, this knob urges the latch 135 rearwardly or in a clockwise direction until it engages the bottom of the slot or groove 142 in the latch holder block 141, due to the lower edge of the bottom of the slot or groove 146a in the control knob engaging the front surface of the latch 135. The downward stroke of the latch 135 should be such that the hook 137 thereon moves out of engagement with the lower surface or with the upper wall of the slot or opening 134 in the gate 123 so the spring 150 may readily cause the latch 135 to move rearwardly at its lower end out of engagement with the gate 123. The reason for moving the latch 135 to this inoperative position is to permit one of the gates 123 and 123' to be operated while the other of the gates remains inoperative in the event that only one of the trackways 35 or 35' has crackers, wafers or the like directed thereto.

Now, when it is desired to move the latch 135 to operative position as shown in Figures 1, 3 and 5, the control knob 146 is merely moved upwardly or in a counter-clockwise direction in Figure 6 to cause the lower end of the latch 135 to be urged forwardly or in a counter-clockwise direction in Figure 6 by the tension spring 150 thereby insuring that the latch 135 is urged towards and against the corresponding gate 123. Thus, upon the next downward stroke of the latch 135, the hook 137 will enter the slot 134 in the gate 123.

The gate latch support bar 144 is disposed above the horizontal plane of the upper surfaces of the block 51 to 55, inclusive, and is also disposed forwardly of the lower portion of a suitable hopper 155 which is preferably made from sheet metal and only a portion of which is shown in Figures 1 and 3. The hopper is adapted to contain a supply of coating or filler material, indicated at F in Figures 8, 9 and 10, and directs the same to the chamber 76 in the pump housing 60. The walls of the hopper 155 are suitably secured at their lower ends to flange members or angle bars 156, as by welding, and these angle bars are, in turn, suitably secured to the upper surfaces of the blocks 51 to 55, inclusive, of the housing 50, as by screws 157. The blocks 51 to 55, inclusive, are provided with suitable threaded bores 160 for reception of the screws 157 as is clearly shown in Figure 2.

Opposite ends of the gate latch support bar 144 extend beyond the outer surfaces of the end or outside blocks 51 and 52 and are suitably secured, as by screws 161, to the front ends of gate operating arms 162 and 163. The gate operating arms 162 and 163 extend rearwardly and are fixedly mounted on opposite ends of a shaft 164 oscillatably mounted in bearing blocks 165 and 166 which are suitably secured, as by screws 167, to the upper surfaces of respective bearing support members or bars 170 and 171. The upper surfaces of these bearing support members 170 and 171 are preferably flush with the upper surfaces of the outside or end blocks 51 and 52 and

are suitably secured to the outer surfaces thereof, as by screws 172 (Figures 2 and 4).

It will be observed in Figures 1 and 2 that the shaft 164 extends outwardly beyond the gate 5 operating arm 162 and has the rear end of a gate crank arm 175 fixed thereon which extends forwardly in substantially parallel relation to the gate operating arm 162 and has the upper portion of a gate crank arm link 176 pivotally mounted in the bifurcated front end thereof by means of a pin 177 which is threadably penetrated by the threaded upper portion of the gate crank arm link 176. The pin 177 is oscillatably mounted in the bifurcated front end of the gate crank arm 175. The upper end of the gate crank arm link 176 extends above the front end of the gate crank arm 175 and has a suitable control knob 180 fixed thereon which may be manipulated by an operator for rotating the gate crank arm link 176 for adjustment purposes and to thereby determine the distance that the gates 123 and 123' will be raised above the base plate 61 (Figure 3) of the housing 50 each time a portion 20 of the viscous filling material in the filling 25 dispensing apparatus is to be discharged from beneath either one or both of the gates 123 and 123'.

The lower end of the gate crank arm link 176 is slidably positioned within a link pilot member 181 and is held thereon by any suitable means, such as a spring clip 182, which is an inverted U-shaped member preferably made from spring wire and having inwardly projecting outwardly curving portions at the lower end of each leg 30 thereof which partially encircle the pilot member 181 and clampingly engage the same to thereby prevent the gate crank arm link 176 from being moved upwardly inadvertently.

The pilot member 181 extends downwardly and 40 is pivotally mounted, as at 185, in the bifurcated rear end of a cam follower arm 186 which is pivotally mounted at its front end thereof, as at 187, on the side frame member 11 of the frame 10. The bifurcated rear end of the cam follower 45 arm 186 has a suitable follower wheel or cam follower 190 rotatably mounted therein which is urged downwardly into engagement with the periphery of a cam wheel 191 by any suitable means such as a tension spring 192. The tension spring 192 is connected at its upper end to a spring anchor 193 projecting from the lower surface of the gate crank arm 175, adjacent the front end thereof, and the lower end of the tension spring 192 is connected, as at 194, to the 55 side frame member 11 of the frame 10.

The cam wheel 191 comprises disk-like plates or cam wheel portions 191a and 191b each having a low surface 195 and a high surface 195a. The cam 191 is an adjustable cam and the 60 disk-like cam wheel portion 191a thereof has a slot 196 therein in which is mounted a screw 197 which is threadably embedded in the other half 191b of the adjustable cam 191. Either one or both of the halves 191a and 191b of the cam 191 are fixed on one end of a cam shaft 200 which is supported and driven by any suitable means such as that shown in said co-pending application, Serial No. 236,617. Of course, the cam 191 is driven at a speed proportionate to the speed of movement of the main conveyor 27 so the gates 123 and 123' will be raised to opened position each time the leading edge of a cracker, wafer or the like W moves forwardly of the front edge of the base plate 61 of the dispensing apparatus (Figures 3, 8, 9 and 10). It is evident that the

high surfaces 195 on opposite halves of the cam 191 will move into engagement with the cam follower 190 as the leading edges of the crackers, wafers or the like W move beyond the front edge of the plate 61. Thus, the link 176 moves upwardly and causes the latches 135 and 135' to move upwardly therewith for raising the gates 123 and 123'.

Now, as either one or both of the gates 123 and 123' are moved upwardly to the opened position, in which the gate 123 is shown in Figure 8, the viscous filling material or peanut butter, which has previously been forced against the inner surface of the lower portion of the gate 123 due to circulation of the peanut butter caused by the gears 82 and 83 (Figure 3), a portion of the viscous filling material or peanut butter, indicated at P in Figures 8, 9 and 10, is forced through the discharge opening 122 and between the lower edge of the gate 123 and the upper surface of the base plate 61 and, thus, passes downwardly by gravity to engage the wafer W adjacent the leading edge thereof. The viscous material will adhere to the upper surface of the wafer W as the wafer continues to move forwardly by means of the conveyor pins 33 and 34.

Now, as heretofore stated, the most important feature of the present invention is the particular manner in which the portion P of the filling material is separated from the bulk of the filling material F disposed within the housing 50. As the low surfaces 194 on each of the cam plates 191a and 191b of the cam 191 move into engagement with the cam follower 190, the latches 135 and 135' are caused to move downwardly by means of the tension springs 192 (Figure 1) and the gates 123 and 123' are also caused to move downwardly to closed position due to the corresponding springs 131.

As the gate 123 moves downwardly, it gradually reduces the size of the opening between the lower edge of the gate and the upper surface of the base plate 61 and thereby squeezes or compresses the viscous material or peanut butter to cause the trailing edge of the portion P to be tapered, as is clearly shown in Figure 10, with the result that the portion of the filling material P is "pinched" off of the bulk of the filling material disposed within the housing 50 of the filling dispensing apparatus.

This "pinching" effect, caused by the lower edge of the gate 123 pressing against the upper surface of the plate 61 at the front edge thereof, tapers the portion P of the filling material to such an extent that a substantially sharp trailing edge is provided thereon and with the result that none of the filling material in the portion P will cling to the gate 23 or to the plate 61. Of course, with continued forward movement of the corresponding wafer W, the trailing edge of the portion P of the filling material F will fall onto the wafer W thus completing the coating operation and after which a second wafer may be positioned upon the portion P of the filling material if so desired.

This unique method of separating the portion P of the filling material from the bulk thereof constitutes one of the most important factors contributing to the successful operation of sandwich making machines of the type shown in my said co-pending applications, since the sandwich or wafer coating machine with which a filling dispensing apparatus of the type described is employed may operate continuously for extended periods far surpassing the periods that similar

machines have been able to operate continuously heretofore without the necessity of stopping the machine periodically to clean the dispensing apparatus.

5 This method of separating the portion P of the filling material from the bulk thereof also results in a uniform coating being applied to each of the wafers W as they are successively passed beneath the filling dispensing apparatus and prevents any portion of the portion P of coating or filling material from clinging to the dispensing apparatus while the remaining portion thereof remains on the corresponding wafer W. Heretofore, in some instances, the entire extruded portion P of the filling material would cling to the dispensing apparatus and the corresponding particular wafer would be entirely devoid of any coating after it had moved past the filling dispensing apparatus, with the result that the sandwich making machine or wafer coating machine would have to be stopped and the wafer W removed from the machine or, if the wafer was permitted to continue through the machine, it would be necessary to again pass this particular wafer through the machine and this would also require that the strip or a portion of extruded filling material would have to be removed from the discharge opening of the filling dispensing apparatus of the type heretofore employed. The 10 latter condition has been completely eliminated by the improved means for parting the viscous material.

In the drawings and specification, there has been set forth a preferred embodiment of the 15 invention and although specific terms are employed, they are used in a generic and descriptive sense only and not for purposes of limitation, the scope of the invention being defined in the claims.

I claim:

- 20 1. In a machine for depositing a viscous coating material onto wafers and the like, coating depositing mechanism comprising a housing having a pair of rotatable shafts therein and a plurality of compartments through which the shafts pass, a pair of intermeshing gear wheels disposed in each compartment and fixed on said shafts, a discharge passageway leading from the bottom of each compartment and to one edge of the coating depositing mechanism, an intake cavity disposed above the gear wheels, a hopper disposed above the intake cavity into which coating material may be placed, means for imparting rotation to the gear wheels to deliver coating material through the discharge passageways, a slidably 25 gate mounted on the housing for opening and closing each of the passageways, disengageable means for engaging the gates for imparting reciprocal motion to the gates to open and close the discharge passageways, means for selectively disconnecting the disengageable means from the gates to cause any one of the gates to remain inoperative, means for normally moving an inoperative gate to closed position, and said housing having a return passageway communicating with each of said discharge passageways and leading back into the intake cavity at a point immediately above the gear wheels whereby unused coating material will be returned into the intake cavity above the gear wheels when not discharged through the discharge passageway.
- 30 2. In a wafer coating machine, a coating dispensing apparatus comprising a gear pump having a plurality of discharge passageways and a return passageway leading from each of the discharge passageways back into the gear pump,

each of the discharge passageways having a discharge opening at one end thereof, a slideable gate fitting over each of the discharge openings, driven means for reciprocating said slideable gates to open and close said openings to allow a coating material to be passed therethrough, selectively operative means for rendering inoperative any one of said slideable gates without interfering with the other slideable gates, said selectively operative means comprising a vertically reciprocating horizontal bar spaced substantially above said gates and having a plurality of latches thereon, there being one of the latches for each of said gates, each of said gates having an opening adjacent the upper edge thereof, each of said latches having a hook portion on the lower end thereof adapted to fit in the opening in the corresponding gate, spring means normally urging the gates downwardly to closed position, means on said horizontal bar for pivotally supporting each of said latches and manually operable control means for varying the position of each of the latches about its axis whereby, upon movement of the control means in one direction, each of the latches will be in engagement with the opening in the corresponding gate and, upon moving any one of the control means in the other direction, one of the latches is swung out of the vertical plane of the corresponding gate thereby moving the hook thereon out of engagement with the opening in the corresponding gate to permit the latch to reciprocate with said bar without opening and closing the corresponding gate.

3. In a machine for depositing a viscous coating material onto wafers and the like, a viscous coating dispensing apparatus provided with at least one discharge passageway adjacent the lower portion thereof and also being provided with means for directing viscous material forwardly along said passageway under pressure; the combination of a relatively thin plate defining the bottom of the passageway and the bottom of the apparatus, a relatively thin gate normally closing the front end of said passageway and being positioned with its front surface substantially flush with the front edge of the plate defining the bottom of said passageway, said gate having a flat bottom edge normally resting upon the upper surface of the plate, automatically operable means for intermittently raising said gate a predetermined distance to thereby permit a portion of the viscous material to be extruded from the passageway between the lower surface of the gate and the upper surface of said plate and to permit the extruded portion of the viscous material to move downwardly by gravity, and means for moving the gate downwardly to ultimately press the bottom edge of the gate against the upper surface of the plate, whereby the flat bottom edge of the gate pinches the viscous material against the upper edge of the plate to thus separate the extruded portion thereof from the portion thereof disposed in said passageway.

4. In a structure according to claim 3, means for supporting said gate comprising a gate support block secured to the front surface of said dispensing apparatus, guide plates disposed adjacent opposite side edges of said gate and against which the gate moves in sliding engagement, a gate confining plate secured against the guide plates, said guide plates being secured against the front surface of the gate support block, and the guide plates being of slightly greater thickness than the gate to permit free sliding movement of the gate.

5. In a wafer coating machine having a viscous coating material dispensing apparatus closely beneath and past whose front end wafers may be successively passed, said dispensing apparatus having at least one substantially horizontal passageway in its lower portion adapted to extend substantially parallel to the path of travel of the wafers and also having means for directing viscous material along said passageway under pressure 10 toward the front end of the dispensing apparatus; the combination of a relatively thin member defining the bottom of said passageway, said member having a flat substantially vertical front edge thereon, a relatively thin flat bottomed substantially vertically disposed gate normally closing the end of said passageway and having its flat bottom normally resting upon the upper surface of said thin member and having its front surface disposed in substantially the same vertical plane 15 as the front edge of said thin member, means operable automatically for raising said gate to provide an orifice between the lower edge of said gate and the upper surface of the member to thereby permit the viscous material to be extruded through said orifice and whereby the viscous material may fall upon the upper surface of a wafer being passed therebeneath, spring means normally urging said gate downwardly to closed position, and means operable automatically 20 for releasing said gate after it has been raised whereby said spring means will urge said gate to closed position and the gate will pinch the viscous material to separate the extruded portion thereof 25 from the portion thereof disposed within the passageway for uniformly coating each successive wafer.

6. In a machine for depositing a viscous coating material onto wafers and the like; coating depositing mechanism comprising a housing having a pair of rotatable shafts therein and a plurality of compartments through which the shafts pass, a pair of intermeshing gear wheels disposed in each compartment and fixed on said shafts, said housing having a discharge passageway leading 40 from the bottom of each compartment and to one edge of the coating depositing mechanism, said housing also having an intake cavity disposed above the gear wheels and into which coating material may be placed, means for imparting rotation to the gear wheels to deliver coating material through the discharge passageways, a slideable gate mounted on the housing for opening and closing each of the passageways, disengageable means for engaging the gates for imparting 45 reciprocatory motion to the gates to open and close the discharge passageways, means for selectively disconnecting the disengageable means from the gates to cause any one of the gates to remain inoperative, means for normally moving an inoperative gate to closed position, and said housing having a return passageway communicating with each of said discharge passageways and leading back into the intake cavity at a point immediately above the gear wheels whereby unused coating material will be returned into the intake cavity above the gear wheels when not discharged through the discharge passageway.

7. In a machine for depositing a viscous coating material onto wafers and the like; coating depositing mechanism comprising a housing having a plurality of compartments therein, a pair of intermeshing gear wheels disposed in each compartment, said housing having a discharge passageway 70 leading from the bottom of each compartment

and to one edge of the coating depositing mechanism, said housing also having an intake cavity disposed above the gear wheels and into which coating material may be placed, means for imparting rotation to the gear wheels to deliver coating material through the discharge passageways, a slideable gate mounted on the housing for opening and closing each of the passageways, disengageable means for engaging the gates for imparting reciprocatory motion to the gates to open and close the discharge passageways, means for selectively disconnecting the disengageable means from the gates to cause any one of the gates to remain inoperative, means for normally moving any inoperative gates to closed position, and said housing having a return passageway communicating with each of said discharge passageways and leading back into the intake cavity at a point immediately above the gear wheels whereby unused coating material will be returned into the intake cavity above the gear wheels when not discharged through the discharge passageway.

8. In a wafer coating machine, a coating material dispensing apparatus having a plurality of discharge passageways, means for directing the coating material into the discharge passageways, said apparatus having a return passageway leading from each of the discharge passageways back into the apparatus, said apparatus having a discharge opening communicating with one end of each of the discharge passageways thereof, a slideable gate fitting over each of the discharge openings, driven means for reciprocating said slideable gates to open and close said openings to allow a coating material to be passed therethrough, selectively operable means for rendering inoperative any of said slideable gates without interfering with the remaining slideable gates, said selectively operable means comprising a vertically reciprocating substantially horizontal bar spaced above said gate and having a plurality of latches for each of said gates, each of said gates having an opening adjacent the upper edge thereof, each of said latches having a hook portion on the lower end thereof adapted to fit in the opening in the corresponding gate, spring means normally urging the gates downwardly to closed position, means on said horizontal bar for pivotally supporting each of said latches, and manually operable control means for varying the position of each

of the latches about its axis whereby, upon movement of the control means in one direction, each of the latches will be in engagement with the opening in the corresponding gate and, upon moving any one of the control means in the other direction, one of the latches is swung out of the vertical plane of the corresponding gate thereby moving the hook thereon out of engagement with the opening in the corresponding gate to permit the latch to reciprocate with said bar without opening and closing the corresponding gate.

9. In an apparatus for dispensing a viscous coating material onto wafers and the like, said apparatus having at least one discharge passageway formed in the lower portion thereof, means for directing viscous material forwardly along said passageway under pressure, and vertically reciprocable means disposed adjacent the front discharge end of said passageway; the combination of a relatively thin plate defining the bottom of said passageway and the bottom of said apparatus, a relatively thin flat gate for closing and opening the discharge end of said passageway and being connected to said vertically reciprocable means, the outer surface of said gate being flush with the front edge of said plate when the gate is in lowered closed position, and the lower surface of said gate being flat and parallel with the portion of the upper surface of the plate which is engageable thereby whereby the flat lower surface of the gate will pinch the viscous material against the upper surface of the plate to separate the extruded portion thereof from the portion thereof disposed in said passageway each time the gate is moved to closed position.
